Application January 21, 1949, Serial No. 71,898

21 Claims. (Cl. 139—291)

1

Our invention relates to means for severing floating strands attached to or woven into a fabric, for producing tufts upon the fabric.

An important object of the invention is to provide automatic means to sever all floating strands in a group, upon one cycle of operation.

A further object of the invention is to provide means of the above-mentioned character which is actuated by the jack lever of the dobby of the loom, after a selected number of picks have been made, to sever the floating strands.

A further object of the invention is to provide means of the above-mentioned character which may be thrown into action and will automatically cause the cutter to travel from one edge of the fabric to the opposite edge and back to the starting point and then idle with respect to travelling.

A further object of the invention is to provide means to effect a reciprocatory movement of the carriage and to utilize such reciprocatory movement for driving a rotary cutter.

A further object of the invention is to provide a presser foot for use in conjunction with the cutter to properly guide the floating yarn into proximity to the cutter to be severed.

A further object of the invention is to provide mechanism of the above mentioned character which is wholly automatic and will not disturb the normal wearing operation of the loom.

Other objects and advantages of the invention will be apparent during the course of the following description.

In the accompanying drawings, forming a part of this application, and in which like numerals are employed to designate like parts throughout the same,

Figure 1 is a plan view of the severing mechanism embodying my invention, showing the same arranged near and above the sand roller of the loom,

Figure 1^a is a detailed section taken on line 1^a—1^a of Figure 1,

Figure 2 is a side elevation of the severing mechanism,

Figure 3 is a plan view of the carriage and track, parts omitted and parts broken away,

Figure 4 is a side elevation of the carriage, the track being omitted,

Figure 5 is an end elevation of the carriage, the track being shown in section,

Figure 6 is a transverse vertical section, taken on line 6—6 of Figure 4;

Figure 7 is a central vertical section through the coupling element securing the chain to the carriage;

2

Figure 8 is an end elevation of the machine, looking to the left in Figure 1,

Figure 9 is a transverse vertical section taken on line 9—9 of Figure 1, looking in the direction of the arrows,

Figure 10 is a plan view of the gear box and associated elements,

Figure 11 is a similar view, the top of the gear box being removed, and parts omitted;

Figure 12 is a vertical section taken on line 12—12 of Figure 10,

Figure 13 is a vertical section taken on line 13—13 of Figure 10,

Figure 14 is a vertical section taken on line 14—14 of Figure 10,

Figure 15 is a diagrammatic plan view of the sand roller of the loom, showing the cutting mechanism associated with the sand roller,

Figure 16 is a diagrammatic vertical section through the sand roller and fabric, showing the position of the carriage,

Figure 17 is an enlarged fragmentary plan view of the fabric, showing the tuft producing yarns woven therein,

Figure 18 is a longitudinal section through the fabric, showing the tuft producing yarn in elevation,

Figure 19 is a section through the fabric showing the completed tuft,

Figure 20 is an enlarged longitudinal section through the presser foot.

In the drawings, wherein for the purpose of illustration is shown a preferred embodiment of our invention, the numeral 20 designates track rails extending transversely of the fabric 21 and loom, and arranged near and spaced from the sand roller 22 of the loom. These track rails may be in the form of inverted L-irons and are rigidly connected and rigidly supported by any suitable means, such as stationary supports 20.

Mounted to travel upon the track rails 20 is a reciprocating carriage 23 embodying a vertical plate 23, having upper horizontal axles 24 rigidly secured thereto, adjacent to its top and opposite ends. The axles 24 carry wheels 25, rotatable thereon, and these wheels travel upon the track rails 20, as shown. The lower transverse axles 26 are rigidly secured to the vertical plate 23 and have wheels 27 rotatable thereon. The wheels 27 are in vertical alignment with the wheels 25 and are arranged beneath the horizontal webs of the track rails 20 and are spaced therefrom. The function of the wheels 27 is to prevent undue vertical movement of the carriage with respect to the track rails 20. A horizontal guide rail 28 is pro-

vided, to engage the ends of two of the wheels 25, and this guide rail is mounted upon the top of one track rail 20, and is adjustably secured to brackets 29 by bolts 30. The brackets 29 are secured to the track rail 20, as shown. Arranged near the right end of the track, Figure 1, which is the starting or idling position of the carriage, is a leaf spring 31, mounted upon and attached to one track rail 20 and adapted to receive a wheel 25 between it and the track rail, when the carriage is shifted to the starting or idling position, thereby securely detachably holding the carriage in the starting or idling position. Since the tops of the rails 20 are horizontal and flat, and the wheels 25 are free from flanges, Figures 1, 3, 5 and 6, the carriage 23' is capable of limited lateral shifting movement in a direction longitudinally of the feed of the fabric being woven. The slack in the endless chain 66 will permit of the limited lateral shifting movement of the carriage 23', which is also contemplated by the adjustment of the guide rail 28. The shoe 49 passes beneath the floating portions 131 to lead the floating portions to the rotary cutter 44, Figure 20, and since the floating portions are arranged in a line, they cause the presser foot 49 to follow such line, thereby shifting the carriage 23' laterally in a forward direction longitudinally of the line of feed of the fabric as it is being woven.

The vertical plate 23 of the carriage depends below the axles 24 and 26 and is provided with a depending vertical bracket 32, rigidly secured thereto. Opposite the bracket 32, the plate 23 has a large opening 33, receiving a tubular hub 34, formed integral with a large gear 35. Arranged within the bracket 32 is a sprocket wheel 36, having a tubular hub 37. The tubular hub 37 telescopes with the tubular hub 34 and is rigidly secured thereto by means of a press fit or the like. Ball bearings 38 are arranged within these telescoping tubular hubs and are mounted upon a horizontal shaft 39, rigidly secured to the vertical bracket 32. A lower horizontal shaft 40 is rigidly secured to the lower end of the vertical plate 23, and carries ball bearings 41, the upper races of which have a press fit within a sleeve 42, which is accordingly rotatable upon the shaft 40. This sleeve is provided at its end adjacent to the vertical plate 23 with a radial flange 43, to engage with a cylindrical rotary cutter 44, having a central opening to receive the sleeve. A pin or pins 45 may attach the rotary cutter to the flange 43. A clamp ring 46 has screw threaded engagement upon the sleeve 42 and is adapted to be screwed up into clamping engagement with the rotary cutter 44. A small gear 47 engages the large gear 35 and has an extension 48 integral with the sleeve 42. The gear 47 is rotatable upon the shaft 40, and is rigidly secured to the sleeve 42 by means of a press fit, but this connection may be effected by other means.

Arranged beneath the cutting edge of the circular cutter 44 is a horizontal presser foot 49, provided upon its upper surface with a rib 50 having a groove 51 to receive the edge of the cutter which of course does not contact with the rib. This rib has a longitudinally inclined upper face which rises toward its trailing end. The rib has its trailing end in vertical alignment with the axis of rotation of the cutter 44 and projects forwardly beyond such axis, as shown. The rear end of the presser foot 49 is preferably bent upwardly slightly, as shown at 52. The leading and trailing edges of the rotary cutter are covered by guards 53 and 54, rigidly secured to the vertical

plate 23, and depending therefrom. The presser foot 49 is carried by a vertical bar 55, offset laterally at its upper portion, and rigidly secured to a depending portion 56 of the plate 23 by bolts 57.

The numeral 58 designates a gear casing, which is rigidly connected with the track rails and rigidly supported with respect to the track rails and has a bearing 59 receiving a transverse shaft 60. The opposite end of this transverse shaft is held within a bearing 61, carried by a bracket 62, rigidly mounted upon the gear casing. Stop rings 63 and 64 are rigidly mounted upon the shaft 60, Figures 10 and 13. A sprocket wheel 65 is clamped to the shaft 60 for rotation therewith and this sprocket wheel receives thereon a sprocket chain 66, extending to the left, Figure 1, and passed about a sprocket wheel 67, fixed upon a rotatable shaft 68, mounted within suitable bearings 69 carried by the track rails 20. The sprocket chain 66 has its upper run attached to the vertical plate 23, near its top, by means of a horizontal tubular coupling 70, Figures 3 to 5 and 7, rigidly secured to the vertical plate 23, and receiving the upper run therethrough. Formed integral with the horizontal tubular coupling 70 is a vertical tube 71, receiving a plug or pin 72, to engage with a selected link and secure such link to the coupling 70. This pin is moved downwardly by a spring 73 engaged by a screw threaded plug 74, having screw threaded engagement with the vertical tube 71. It is thus seen that when the sprocket chain 66 is moved in opposite directions, the carriage will be reciprocated. The lower run of the sprocket chain 66 engages with the sprocket wheel 36, and when the lower run is travelling in one direction, the carriage is travelling in the opposite direction, and the sprocket chain will therefore rotate the sprocket wheel 36 which will rotate the cutter 44 at a high speed through the medium of the gearing including gears 35 and 47.

Means is provided to rotate the shaft 60 in opposite directions, including gears mounted within the casing 58. This casing has a top or cover 75. The gearing includes a gear 76, arranged within the gear casing 58 and rigidly mounted upon the end of the transverse shaft 60. The gear 76 is adapted to be alternately engaged by axially shiftable gears 77 and 78, and also to be free from engagement with both gears at the same time. The gears 77 and 78 are rigidly mounted upon a longitudinally movable shaft 79, Figure 11, mounted within bearings 80 and 81. The shaft 79 has a head 82 rigidly mounted thereon, provided with an annular groove receiving a shifting stud 83, rigidly secured to a reciprocating bar 84. The bar 84 is guided within openings 85 and 86, and the bar 84 extends exteriorly of the gear casing and has a screw threaded extension 87. This extension has a screw threaded opening 88 to receive a bolt 89, locked in adjustment by nuts 90. This bolt has a screw threaded connection with a slide 91, operating within a guide 92. The slide 91 has a cam point 93 and the shaft 79 has a cam point 94, these cam points being oppositely arranged. A transverse shaft 95 is provided and is arranged at a right angle to the shaft 79, and is held within bearings 96, Figure 11. This transverse shaft extends to the exterior of the gear casing and has a vertically swinging lever 97 rigidly secured thereto. Mounted within the gear casing is a cam 98, rigidly mounted upon the transverse shaft 95. This cam has a low part 99, intermediate parts 100, and high part 101, Figure 12. The

5

cam points 93 and 94 are arranged to engage these cam parts, as shown:

The lever 97, Figures 10, 12 and 1, operates within a stationary guide including spaced sides 102. One side has a transverse opening for receiving a bolt 103, having a beveled face 104. This bolt is carried by a shank 105, which engages arm 106. The bolt is projected to the locking position by a spring 107. In Figure 10, the bolt is projected to a locking position to lock the lever 97 against movement. The shank 105 extends through an opening formed in one arm of a bell crank lever 108 and carries a stop collar 109. This bell crank lever is mounted upon a fixed pivot 110, carried by the cover 15. When the lever 108 has its transverse arm swung to the left, as indicated by the arrow in Figure 10, the bolt 103 will be retracted and the lever 97 released.

Arranged near and above one track rail 20 is a horizontal reciprocating shifting bar 111, operating within stationary guides 112. At its right end, Figure 1, the bar 111 has an upstanding projection 113, Figure 8, arranged to contact with the transverse arm of the bell crank lever 108 and swing it to the left, as indicated by the arrow, when the bar 111 is moved to the left. Rigidly mounted upon the bar 111 is a trip or extension 114, having a depending end 115, Figure 9, arranged in the path of travel of the right axle 24. The bar 111 has a second trip element 116 rigidly secured thereto, having a depending end 117 arranged in the path of travel of the other axle 24, like end 115. A trip 118 is rigidly mounted upon the bar 111, and arranged to engage the lever 97 to move it to the neutral or intermediate position.

A retractile coil spring 118 has one end attached to a stationary bolt 119 on one rail track 20 and its opposite end secured to the bar 111, as shown at 120. A retractile coil spring 121 has one end secured to the bar 111 by a bolt 122 while its opposite end is secured to the lever 97, as shown at 123, Figure 12.

A wire 124 or other flexible element is attached to the lever 97 at 125 and this wire extends through a guide tube 126 and the wire extends to the dobby head of the loom and is connected with the jack lever 126 thereof. The shaft 79 is continuously rotated by a sprocket wheel 79', driven from any suitable source.

The operation of the machine is as follows:

As more clearly shown in Figures 1, 15 and 16, the track rails 20 are positioned near and above the sand roller 22 of the loom, but the carriage plate 23 and presser foot 49 are spaced from the periphery of the sand roller and the presser foot does not contact with the sand roller. This enables the fabric to flex as the presser foot is travelling over the upper surface of the fabric.

As the fabric is woven upon the loom, it is passed over the sand roller 22 and is wound upon the take-up roll beneath the sand roller. This is the conventional procedure. During the weaving of the fabric, the tuft producing strands 129 extend longitudinally of the fabric and are woven into the fabric. This weaving action is well known in the art and is shown generally in Patent No. 2,087,770 and other patents. By virtue of the weaving action the longitudinal strands 129 pass transversely through the completed fabric, providing short portions 130, and long floating portions 131 arranged above the fabric, during the weaving process. The short portions 130 constitute the means which secure the completed tufts to the fabric, and these short portions 130 are

6

arranged in spaced longitudinal groups and spaced transverse groups. The short portions 130 are woven into the fabric holding the ends. The long floating portions 131 are severed at their longitudinal centers, while the fabric is moving toward the breast beam, thus producing W-shaped tufts, Figure 19. Since the guide rail 28 is longitudinally inclined with respect to the longitudinal axis of the sand roller and transverse axis of the fabric, the wheels 25 by bearing against the inclined guide rail 28 cause the carriage to move slightly longitudinally of the fabric while the carriage is being shifted transversely of the fabric and this causes the rotary cutter 44 to keep up with the feed of the fabric and sever the long floating portions 131 at their longitudinal centers. The upper run of the chain 66 tends to pull the carriage in a straight line and retains the wheels 25 in contact with the guide rail 28, but there is sufficient slack in the upper run to permit of the slight lateral shifting of the carriage. These W-shaped tufts are securely anchored to the fabric. When the fabric is laundered or otherwise treated, these tufts become fluffy. The tuft producing yarn 129 is much heavier than the warp of the fabric and is of a much looser twist, so that it will readily fluff. The presser foot 49 passes beneath the floating portions 131 and these floating portions travel upon the inclined rib and are brought into contact with the rotating cutter 44 projecting into the groove 51 and are severed thereby. The severing occurs before the shank 55 reaches the floating portions 51.

The weaving is continuous and the transverse rows of short portions 130 may be spaced any selected distance. We have found that 4½ inches gives satisfactory results and this spacing is effected by 56 picks of the loom. When the spacing of the transverse rows of short portions is 4½ inches, the longitudinal rows are also spaced 4½ inches, so that the tufts appear in square groups. Of course the invention is not necessarily restricted to this arrangement, as the groups may be staggered. During the weaving period, the carriage 23 may be idling at the starting position at the right side of the machine, Figure 1. When the carriage is idling, the lever 97 is in the neutral or intermediate position and the cam 93 is turned to bring the cam points 93 and 94 into engagement with the intermediate cam parts 100, and shaft 79 is shifted so that the bevel gears 77 and 78 both disengage bevel gear 76. The idling continues until the weaving has progressed so that the sand roller 22 has advanced the woven fabric so that the longitudinal centers of the floating portions 131 of the next transverse row are in substantial alignment with the rotary cutter 44 and when this occurs, the jack lever 126 of the dobby head is operated and pulls the wire 124 to the right, Figures 1 and 2. When this occurs, the lever 97 is swung to the right, Figures 10 and 12; and the bolt 103 now engages in front of this lever 97, locking it in the outward position. When the lever 97 is turned to the right, Figure 12, the cam point 93 engages the low part 99 of the cam 98 and the cam point 94 engages the high part 101. These parts now occupy the position shown in Figure 12, and the bar 84 has shifted to the right and the shaft 79 shifted to the right and the bevel gear 77 brought into engagement with the bevel gear 76, while the bevel gear 78 remains out of engagement with the bevel gear 76. The shaft 79 is continuously driven and this shaft is rotating in the direction of the arrow, Figure 12. This

is clockwise when viewed from the right, in Figures 1, 2, 11 and 12, and the bevel gear 71 rotates bevel gear 76 in the direction of the arrow, counterclockwise, Figures 10, 11 and 12. The shaft 60 is therefore driven counterclockwise in the direction of the arrow, Figure 1, and the upper run of the sprocket chain 66 is travelling to the left, Figure 1. Since the vertical plate 23 of the carriage is secured to this upper run, the carriage is now shifted longitudinally to the left, and the presser foot 49 will pass beneath the floating strand portions 131 in the transverse row and they will be severed. When the carriage is travelling to the left, the spring 118 shifts the bar 111 to the left so that the trip 113 is adjacent to the lever 108, but spring 118 is not strong enough to swing bell crank lever 108 upon its pivot. When the carriage approaches the end of its travel to the left and all floating strand portions have been severed, the leading axle 24 will contact with the depending portion 117 of the trip 116 and the shifting bar 111 will be shifted further to the left to swing the bell crank lever 108 upon its pivot. When the lever 97 is locked in the position to the right, spring 121 is under tension, and this spring will swing the lever 97 to the left when such lever is released and the tension of the spring 121 will then be relieved. When the bar 111 is shifted to the left by the carriage, the trip 113 swings the bell crank lever 108 in the direction of the arrow, Figure 10, whereby the bolt 103 is moved out of the path of travel of the lever 97. This lever 97 being free, the spring 121 quickly shifts the lever 97 to the extreme left position, the jack lever 126' being in the original position. When this occurs, the cam 98 is turned so that the cam point 93 contacts with the high part 101 and the cam point 94 contacts with the low part 99. This shifts the bar 84 and shaft 79 to the left and brings the bevel gear 78 into engagement with the bevel gear 76, and the bevel gear 77 out of engagement with the bevel gear 76. The shaft 79 continuing to rotate in the same direction, the direction of rotation of the gear 76 and shaft 60 is reversed and the upper run of the sprocket chain 66 travels to the right, moving the carriage to the right. When the carriage approaches the end of its travel, to the right, the leading axle 24 contacts with the depending extension 115 of the trip lever 114 and the bar 111 is shifted to the right. The trip 118' now contacts with the lever 97 and swings it to the right and this turns the cam 98 so that the cam points 93 and 94 engage the intermediate cam parts 100. This shifts the shaft 79 to the intermediate position and moves bevel gear 78 out of engagement with bevel gear 76 and retains bevel gear 77 out of engagement with bevel gear 76. The shaft 79 is now disconnected from the shaft 60 and the carriage will idle at the starting position. This idling will continue until the jack lever of the dobby head again pulls the wire 124 to the right. Thus it is seen that during the major portion of the weaving periods the carriage is idling, and the carriage is automatically thrown into action at intervals, and makes a forward stroke and a back stroke in a continuous manner, and again idles.

It is to be understood that the form of our invention herewith shown and described is to be taken as a preferred example of same and that various changes in the shape, size, and arrangement of parts may be resorted to without departing from the spirit of our invention or the scope of the subjoined claims.

Having thus described our invention, we claim:

1. In a machine for severing floating yarn portions upon a fabric, a track, a carriage mounted upon the track, means to sever the floating portions including a power operated cutter mounted upon the carriage, means to move the carriage in opposite directions and connected therewith and including a gear, a pair of driving gears arranged near the first named gear, and cam operated means to shift the pair of driving gears so that they both disengage the first named gear and then alternately move one driving gear into engagement with the first named gear while the other driving gear disengages the same.
2. In a machine for severing floating yarn portions upon a fabric, a track, a carriage mounted upon the track, means to sever the floating portions including a power operated cutter mounted upon the carriage, means connected with the carriage to move it in opposite directions and including a bevel gear, a pair of driving bevel gears arranged near the first named bevel gear, and cam means to shift the driving bevel gears axially so that they both disengage the first named bevel gear and then alternately move one driving bevel gear into engagement with the first named bevel gear while the other driving bevel gear disengages the same.
3. In a machine for severing floating yarn portions upon a fabric, a track, a carriage mounted upon the track, means to sever the floating portions including a power operated cutter mounted upon the carriage, means connected with the carriage to move it in opposite directions and to then idle including reversible gearing, actuating means for the reversible gearing including a movable element, a shifting device arranged near the carriage and having parts disposed in the path of travel of the carriage to be moved thereby, a trip secured to the shifting device and arranged to engage the movable element and move it to the neutral position so that the gearing will cause the carriage to idle, means connected with the movable element and adapted to shift the same in one direction beyond the neutral position so that the gearing moves the carriage in one direction, latch means for releasably locking the element when shifted to the last named position, operating means connected with the latch means and actuated by the shifting device to cause the latch means to release the movable element, and operating means connected with the movable element to shift it in an opposite direction beyond the neutral position when such element is released by the latch means.
4. In a machine for severing floating yarn portions upon a fabric, a track, a carriage mounted upon the track, means to sever the floating portions including a power operated cutter mounted upon the carriage, means connected with the carriage to move it in opposite directions and to then idle including reversible gearing, cam means for controlling the operation of the reversible gearing, a lever connected with the cam means, a shifting device arranged near the carriage and having trips to be engaged by the carriage so that the carriage moves the shifting device in opposite directions, a trip secured to the shifting device and arranged to engage the lever and move it to the neutral position so that the gearing will cause the carriage to idle, a jack lever operated means connected with the lever to shift the same in one direction beyond the neutral position so that the gearing moves the carriage in one direction, releasable latch means for locking the lever against movement when shifted to the last named

position and operated by the shifting device to release such lever, and automatic means connected with the lever to shift it in an opposite direction beyond the neutral position when the lever is released by the latch means.

5. In a machine for severing floating yarn portions upon a fabric, a track, a carriage mounted upon the track, means to sever the floating portions including a power operated cutter mounted upon the carriage, means connected with the carriage to move it in opposite directions and to then idle including a bevel gear, an axially movable rotatable driving element arranged near the bevel gear, bevel gears mounted upon the driving element to rotate therewith and spaced a greater distance than the diameter of the first named bevel gear so that both bevel gears disengage therewith when the driving element is shifted axially to the neutral position, cam operated means to shift the driving element axially, a lever connected with the cam operated means to actuate the same, a shifting device arranged near the carriage and having trips disposed in the path of travel of the carriage so that the shifting device is moved in the opposite directions by the carriage, a trip secured to the shifting device and arranged to engage the lever and shift the same to a neutral position to cause the carriage to idle, operating means connected with the lever to move it in one direction beyond the neutral position so that the carriage is driven in one direction, a latch to releasably lock the lever in the last named position, a pivoted lever to operate the latch to release the lever, a trip carried by the shifting device to operate the pivoted lever, and a spring to move the first named lever in an opposite direction when released beyond the neutral position so that the carriage is moved in an opposite direction.

6. In a machine for severing floating yarn portions upon a fabric, a track, a carriage mounted upon the track, means to sever the floating portions including a power operated cutter mounted upon the carriage, driving means connected with the carriage to move it in opposite directions and to then idle, a movable element connected with the driving means, means operated by the movement of the carriage and engaging the movable element to shift it to the neutral position, jack lever operated means connected with the movable element to shift it in one direction beyond the neutral position, a releasable latch device to lock the movable element in the last named position, means operated by the movement of the carriage to actuate the latch device to release the movable element, and automatic means connected with the movable element to shift the same in an opposite direction beyond the neutral position when released.

7. In a machine for severing floating yarn portions upon a fabric, a track, a carriage mounted upon the track, means to sever the floating portions including a power operated cutter mounted upon the carriage, driving means connected with the carriage to move it in opposite directions and to then idle, said driving means including an axially movable element, a cam device to shift the axially movable element including a pivoted cam having a low part, intermediate parts and a high part, a lever connected with the cam to turn it, jack lever operated means connected with the lever to shift it in one direction beyond the neutral position, a releasable latch device to lock the lever in the last named position, means operated by the movement of the carriage to actuate the

latch device to release the lever, and automatic means connected with the lever to shift the same in an opposite direction beyond the neutral position when released.

5. In a machine for severing floating yarn portions upon a fabric, a track, a carriage to travel longitudinally upon the track, a flexible endless element connected with the carriage to move it longitudinally of the track, a presser foot mounted upon the carriage, a rotary cutter mounted upon the carriage near the presser foot, and gearing to drive the rotary cutter including an element engaging the flexible element to be driven thereby.

15. In a machine for severing floating yarn portions upon a fabric, a track, a carriage mounted upon the track, means to move the carriage including an endless element having upper and lower runs, the upper run being attached to the carriage, means to sever the floating yarn portions including a rotary cutter, and gear means driving the rotary cutter and including a rotary element engaging the lower run.

20. In a machine for severing floating yarn portions upon a fabric, a track, a carriage to travel upon the track, an endless sprocket chain extending longitudinally of the track and including upper and lower runs, an attaching device connecting the upper run with the carriage, 25. spaced sprocket wheels carrying the endless sprocket chain, means connected with one sprocket wheel to drive it, a presser foot mounted upon the carriage, a rotary cutter mounted upon the carriage near the presser foot, gearing mounted upon the carriage to drive the rotary cutter including a sprocket wheel to engage the lower run.

30. In a machine for severing floating yarn portions upon a fabric, a guide device, a carriage to travel upon the guide device, means to sever the floating yarn portions including a cutting element mounted upon the carriage, means connected with the carriage to move it longitudinally of the guide in opposite directions and to then cause the carriage to idle and including a control element, jack lever operated means connected with the control element to move it in one direction, means moved by the carriage to move the control element in one direction, a releasable latch to hold the control element in one position, means moved by the carriage to actuate the latch to release the control element, and automatic means connected with the control element to shift it in one direction when released.

35. In a machine for severing floating yarn portions upon a fabric, a track, a carriage to travel upon the track, means for severing the floating yarn portions mounted upon the carriage and including a power driven cutter, driving

40. means connected with the carriage to move it in opposite directions and then cause the same to idle including a control element, jack lever operated means connected with the control element to shift it in one direction beyond the neutral position, trip means moved by the carriage to shift the control element to the neutral position, a latch device to releasably hold the control element in one position, trip means moved by the carriage to actuate the latch device to release the control element, and automatic means connected with the control element to move it when released in an opposite direction beyond the neutral position.

45. In a machine for severing the floating portions of a group of tuft forming strands carried

11

by a fabric, an endless operating element extending longitudinally of the group, a presser foot connected with the endless operating element to be shifted thereby and movable along the fabric to pass beneath the floating portions, and a rotary cutter arranged near and above the presser foot and traveling therewith, and means engaging the endless operating element and operated thereby and serving to rotate the cutter.

14. In a loom, a guide element over which the fabric passes when being woven with tuft forming strands having floating portions arranged in transverse rows, a power operated mechanism to sever the floating portions and movable longitudinally of each row of floating portions to be severed, said mechanism including a cutter movable with relation to the longitudinal travel of the mechanism, means to guide the power operated mechanism during its longitudinal movement of the row and to shift said mechanism transversely of the row so that the cutter severs the floating portions in succession substantially at their longitudinal centers, and means connected with the power operated mechanism to shift the same longitudinally of the row while the fabric is being woven.

15. In a loom, a guide element over which the fabric passes when being woven with tuft forming strands having floating portions arranged in transverse rows, a track extending longitudinally of the guide element, a carriage to travel upon the track and guided by the track longitudinally of each transverse row of floating portions in succession shiftable laterally in a direction longitudinally of the feed of the fabric being woven, a power operated cutter mounted upon the carriage and movable with relation thereto to sever the floating portions in each roll in succession, a presser foot secured to the carriage for movement therewith and passing beneath the floating portions to guide the floating portions to the cutter, driving means connected with the carriage to move it longitudinally of the track, a jack lever of a dobby, and connecting means between the jack lever and the driving mechanism so that the driving mechanism is set into action by the movement of the jack lever.

16. In a loom, a guide element over which the fabric passes when being woven with tuft forming strands having floating portions arranged in transverse rows, a track extending longitudinally of the guide element, a carriage to travel upon the track and guided by the track longitudinally of each transverse row of floating portions in succession to be severed and shiftable laterally in a direction longitudinally of the feed of the fabric being woven, a power operated cutter mounted upon the carriage and movable with relation thereto to sever the floating portions in the row in succession, a presser foot mounted upon the carriage to move therewith and arranged to pass beneath the floating portions to guide such floating portions to the power operated cutter driving means connected with the carriage to move it longitudinally of the track while the fabric is being woven, and means set into action by a movable part of the loom and connected with the driving means to actuate the driving means.

17. In a loom, a guide element over which the fabric passes when being woven with tuft forming strands having floating portions arranged in transverse rows, a track extending longitudinally of the guide element, a carriage to travel upon the track and guided by the track longitudinally of each transverse row of floating portions in suc-

12

cession to be severed and shifted laterally by such track during its longitudinal movement, a power operated cutter mounted upon the carriage and movable with relation thereto to sever the floating portions in a row in succession, and driving means connected with the carriage to shift the same longitudinally from the starting position and return the carriage to the starting position and then cause the carriage to idle at the starting position.

18. Fabric guide means, said fabric having woven therein tuft forming strands having floating portions arranged in rows, a track extending longitudinally of the rows, a carriage to travel upon the track, a presser foot mounted upon the carriage and arranged to contact with the face of the fabric and to pass beneath the floating portions and raise such floating portions, a rotary cutter mounted upon the carriage and arranged near and above the presser foot to sever the floating portions, an endless driving element extending longitudinally of the track and having one run connected with the carriage, a rotary element mounted upon the carriage and engaging the other run of the endless element to be driven thereby, and speed increasing gearing mounted upon the carriage and driven by the rotary element and driving the rotary cutter.

19. Fabric guide means for receiving fabric thereon as it is being woven for providing tuft forming strands having floating portions arranged in transverse rows, a track extending longitudinally of the fabric guide means and transverse rows, a carriage to travel upon the track, a presser foot mounted upon the carriage and arranged to contact with the face of the fabric, the presser foot having a part to raise the floating portion, a rotary cutter mounted upon the carriage and disposed near and above the presser foot and rotating in a substantially vertical plane extending longitudinally of the track to sever the floating portions in succession when the carriage is moved longitudinally of the track, driving means connected with the carriage to move the same longitudinally of the track and to move the rotary cutter throughout substantially the entire length of the transverse row of floating portions, a jack lever of a dobby, connecting means between the jack lever and the driving means so that the driving means is set into action by the movement of the jack lever, and means to drive the rotary cutter.

20. An attachment for a loom on which is woven a fabric having tuft cords lying parallel to the fabric warp, said cords being woven in the fabric at spaced intervals in the length of the fabric so as to provide tuft loops, the loops in adjacent cords being substantially aligned in rows transversely of the fabric, said attachment comprising, in combination, guide means mounted on the loom and extending across the fabric, a cutting device mounted on said guide means for reciprocation lengthwise of said guide means and across said loops to engage and sever the latter, and means operable in timed relation with said loom for effecting reciprocation of said cutting device on said guide means, whereby said loops are severed to form a tufted fabric, said cutting device comprising a shoe dimensioned and shaped to pass between said tuft loops and said fabric, a cutting blade positioned adjacent said shoe for engaging and cutting said loops while said shoe is passing between the loop to be cut and the fabric, a common support for said shoe and said blade, and means mounting said support

13

for displacement lengthwise of said fabric, whereby said shoe may guide said blade into the correct position for the severing of the loops regardless of slight misalignment of the loops in a given row.

21. In a loom for weaving fabric, said loom having means for floating selected warp yarns to form floating portions on the upper face of the fabric, an improved float cutting apparatus for severing the floated portions of the selected warp yarns comprising a carriage, means for moving the carriage from one side of the loom to the other, at least one driven rotary cutting disk supported by the carriage, and disposed above the path of travel of the fabric being woven, the axis of said cutting disk being parallel to the warp yarns, means extending radially of said cutting disk and from opposed sides of the cutting disk for passing beneath the floated warp threads and directing the floated warp yarns to the cutting disk upon movement of the carriage across the loom and means allowing movement of the means

5

14

for passing beneath the floated warp threads and the cutting disk longitudinally of the direction of travel of the fabric being woven.

JOSEPH KELLY McCUTCHEON.
